US0D1060094S

(12) **United States Design Patent** (10) Patent No.: **US D1,060,094 S**
(45) Date of Patent: ** Feb. 4, 2025

(54) **AUTHENTICATION TAG**

(71) Applicant: **eBay Inc.**, San Jose, CA (US)

(72) Inventors: **Alan Vinogradov**, Nyack, NY (US);
Barris Vinogradov, Brooklyn, NY (US)

(73) Assignee: **eBay Inc.**, San Jose, CA (US)

(**) Term: **15 Years**

(21) Appl. No.: **29/883,381**

(22) Filed: **Jan. 27, 2023**

Related U.S. Application Data

(63) Continuation of application No. 16/436,850, filed on Jun. 10, 2019, now abandoned.

(51) **LOC (15) Cl.** **10-05**

(52) **U.S. Cl.**

USPC **D10/106.9**

CPC **G06Q 30/0185** (2013.01); **G06K 19/10** (2013.01); **G06Q 20/40145** (2013.01); **G06K 7/10722** (2013.01)

(74) *Attorney, Agent, or Firm* — FIG. 1 Patents

(57) **CLAIM**

The ornamental design for an authentication tag, as shown and described.

DESCRIPTION

FIG. 1 is a top, front, right-side perspective view of an authentication tag;

FIG. 2 is front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines depict portions of the authentication tag that form no part of the claimed design.
